UNITED STATES PATENT OFFICE.

FRANCIS L. LORD, OF NEWARK, NEW JERSEY, ASSIGNOR, BY DIRECT AND MESNE ASSIGNMENTS, TO THE LORD LABORATORIES, INC., OF NEW YORK, N. Y., A CORPORATION OF SOUTH DAKOTA.

MOUNTING MEANS FOR RADIO RECEIVING SETS.

Application filed August 28, 1925. Serial No. 53,003.

This invention relates to adjustable mounting means for variable coils of radio receiving sets.

An object of this invention is to provide 5 suitable mounting means for settable coils for attaining varied inductive relation to another coil, fixed or movable, for varied inductive and capacitance effects, singly and both.

10 Pursuant to a more preferred form of my invention, the movable coil is mounted on a shaft for rotary setting, the coil being positioned to have its axis extending at an angle to the axis of the shaft, and associated with 15 one or more fixedly mounted coils, the axis of which extends at an angle to the axis of said shaft, whereby at a given position of such rotatably settable coil, the axis of said rotatably settable coil is substantially parallel to and if desired, substantially in coincidence with, the axis of said coil or coils.

In the most preferred forms of my invention, the rotatably settable coil is mounted 20 on the shaft of a rotary variable condenser, 25 as in a radio frequency stage or in a detector stage, the rotatable coil being positioned normally to have its axis in parallel or in substantial coincidence with the other coil when the rotor plates of the condenser are 30 at a predetermined position relative to the stator plates, usually at full capacitance value.

35 Preferably, the rotor coil is mounted on its shaft to permit of adjustment of the rotor coil relative thereto, as by rotary adjustment by means of a worm and a worm gear or the like, which adjustment serves to compensate for variations in capacitance and induction, each or both, of the antenna circuit, ground circuit or for variations in the individual parts of the radio frequency and detector circuits of the radio receiving set.

40 Further features and objects of the invention will be more fully understood from 45 the following detail description and the accompanying drawings, in which

50 Fig. 1 is a side elevation showing my invention applied to a set of coils in combination with a variable oscillation condenser of the rotary type;

Fig. 2 is a rear elevation of Fig. 1;

Fig. 3 is a sectional elevation on line 3—3 of Fig. 2;

Fig. 4 is a sectional elevation on line 4—4 of Fig. 3; and

Fig. 5 is a sectional elevation on line 5—5 of Fig. 3.

My invention is applicable generally for the use of a rotor coil, the position of which it is desired to adjust to attain variable inductance and capacitance effects relative to one or more other coils, as will appear more fully hereinafter.

The structure particularly set forth in the drawings is applicable to a radio receiving system of the type set forth in my co-pending application Serial No. 15,082, filed by me on the 12th day of March, 1925, now Patent 1,571,900, and entitled Tuned radio frequency receiving system, wherein I have 60 set forth and claimed a tuned radio frequency system provided with a radio frequency transformer or coupler or like variable capacitance and inductance device, which is set in position for various settings 65 of the condenser. More particularly, in the specific circuit arrangement set forth in my aforesaid co-pending application Serial No. 15,082, the primary of a radio transformer, 70 coupler or the like, is formed of a coil part in fixed inductive relation to the secondary coil, the primary coil further comprising a rotor coil connected in series with said fixed primary coil part, which rotor coil is set in 75 position concurrently with the setting of the variable condenser and to like arcuate extent, as by suitably mounting the rotor coil on the shaft of the rotary variable condenser.

The drawings of the present application 80 illustrate a preferred form of mounting of the fixed primary and secondary of a radio frequency transformer, coupler or the like and the mounting of the rotor coil on the 85 shaft of a rotary variable condenser.

The rotary variable condenser is indicated 90 generally in Fig. 1 at 10 and may be of any approved or any preferred construction, embodying the shaft 11 suitably mounted at the forward end, as in the front end plate 100 (not shown) and similarly rotatably mounted at its rearward end 12 in the rear end

plate 13. The rotor plates of the condenser 10 are indicated at 14. The stator plates 15 are usually mounted on spaced rods 16, 16, usually three in number, and but two of which are shown in Fig. 1.

The rotor coil indicated at 17 is mounted on the rotatable bracket 18, the hub 19 of which is recessed as indicated at 20, see Figs. 1 and 3, to receive the end 12 of the rotor shaft 11 of the condenser. The end 12 of the rotor shaft 11 may be flattened or squared and the recess 20 correspondingly shaped, to insure rigidity of arcuate relation of the bracket 19 relative to the rotor shaft 11. The set screw 21 serves to fix the position of the hub 19 on the end 12 of the rotor shaft 11. The rotor coil 17 is preferably received within the peripheral groove 22, to locate the coil 17 to have its axis at a predetermined angle to the axis of the condenser 11. Such angle may be 45 arcuate degrees, as indicated in the drawings.

The securing of the rotor coil 17 at its outer end face may be had by the face plate 23 at the outer end of the bracket 18 and secured by the screw 24 or the like. The face plate 23 is preferably provided with the extension 25 having the perforation 26 through which pass the leads 27, 28, connected to the opposite ends of the rotor coil 17; the extension 25 and perforations 26 is preferably directed substantially in alignment with the axis of the condenser shaft 11, thus protecting the leads 27, 28 from twisting or other lateral strain. The leads 27, 28 may be anchored on the bracket 18 by means of the ring 29. The terminals of the rotor coil 17 and those of the leads 27, 28 may be brought within the recess 18^a and soldered, and the ring 29 positioned within the recess 18^a.

The end plate 23 may be provided with the inwardly directed extension 23^a, received within the recess 18^a.

The outer end portion 30 of the bracket 18 provided with the groove 22 for the rotor coil 17 is preferably adjustable relative to the hub 19 of the bracket 18, to permit the adjustment of the rotor coil 17 relative to the axis of the condenser shaft for any particular setting of the condenser plates 14, 15. Such adjustment is afforded by reason of the positioning of the axis of the rotor coil being at an angle to the axis of the condenser shaft 11.

As one form of rotary adjustment, I have shown the end portion 30 of the bracket 18 provided with the circular recess 31 for receiving the circular stud 32 of the hub 19, the forward end of which is provided with the worm gear 33; such worm gear 33 may be machined at the end of the stud 32. The end portion 30 of the bracket 18 is circularly recessed at 34 co-acting with the worm gear 33. The end portion 30 of the bracket 18 is

also preferably slotted as indicated at 36 and the clamping screw 37 disposed in registering recesses one of which is threaded, to locate the screw 37 transversely to the slot 36, for the purpose of exerting and releasing pressure of the material of the end portion 30 relative to the worm 35, the purposes of which are set forth more fully hereinafter.

The hub 19, including its stud portion 32 and worm gear 33, are preferably formed of brass or like material, which is readily machined by simple operations. The end portion 30 of the bracket 18 is preferably of bakelite or like moldable material.

The worm 35 is preferably formed to have the enlarged circular portion 38 snugly received within the circular perforation 34, and also provided at one end with the enlarged knurled head 39 for manual manipulation of the worm 35. The opposite end of the worm 35 may be reduced in diameter as indicated at 40 and provided with the end member 41 of enlarged diameter, positioned exteriorly of the perforation 34 and the intermediately positioned, circularly reduced portion 42 snugly received within the perforation 34. The end member 41 may be secured by its set screw 43.

Accordingly, upon loosening the clamping screw 37, to release the spaced portions of bakelite or the like relative to the circular portion 38 of the screw 35 and circular portion 42 of the end member 41, the screw 35 may be manually rotated in either direction as desired, whereupon by reason of the meshing relation of the worm 35 with the fixed worm gear 33, the end portion 30 of the bracket 18 is positively adjusted by rotative movement relative to the fixed hub portion 19, thereby adjusting the relation of the axis of the rotor coil 17 relative to the axis of the condenser shaft 11. Upon attaining the desired adjustment of the rotor coil 17, the clamping screw 37 is re-set to its tightened position, thus locking the worm gear 35 relative to the end portion 30 of the bracket 18 and thereby relative to the hub 19. The fixed or other primary coil part and the secondary coil are indicated at 44, mounted in close and coupling to one another, usually in fixed position, either one of which may be the inner coil and the other the outer coil. The combined coils 44 are suitably fixedly mounted by means of a bracket 45, of bakelite or the like, secured by one or more positioning screws 46 to the end plate 13 of the condenser 10.

The bracket 45 may be provided with the groove 47 and at its outer face with the arcuate clamping plate 48 of bakelite or the like secured in position by one or more positioning screws 46. The clamping plate 48 may also serve as a support for the terminals 50 for the respective leads, the terminals 50 in this instance being five in number,

namely by reason of one terminal of the fixed primary part being connected to ground jointly with one terminal of the secondary coil, thus also connected to ground, which joint terminal and the other primary terminal, the remaining secondary terminal and the two leads 27, 28 of the rotor coil 17 total five as aforesaid.

The arcuate portion of the clamping plate 48 is indicated by 48^a, as appears in full view in Fig. 2. The bracket proper 45 may be provided with the arcuate projecting portion 45^a which combines with the arcuate portion 48^a of the clamping plate 48 to serve 10 as coacting clamps for the combined coils 44, for attaining enhanced rigidity and simplicity of assembly and dis-assembly.

The above construction is applicable generally for fixed rotor coil parts of radio 20 transformers, couplers and the like, or individually for general use of a rotor coil alone, that is to say, without a fixed coil in inductive and capacitance relation therewith.

Applied to my aforesaid co-pending application Serial No. 15,082, as a four or five tube set, including two radio frequency stages, a rotor coil corresponding to the aforesaid rotor coil 33 is assembled on the three variable condensers in the manner above set forth, the 30 circuit connections of the coils being carried out pursuant to the circuit connections of my aforesaid application or pursuant to any approved circuit arrangement as desired.

Normally, for a tuned radio frequency receiving system as set forth in my aforesaid application Serial No. 15,082, the rotor coil is set to the position indicated generally in Fig. 1 for the reading of "100" on the markings of the dial of the condenser, that is to 35 say, with the rotor plates in substantially full common area relation with the stator plates, i. e., for substantially the maximum capacity value of any particular condenser, as is indicated by the relative positions of the rotor plates 14 relative to the stator plates 15 in Fig. 1.

However, when it is desired to adjust the position of the rotor coil 17 relative to the fixed secondary or the combined fixed primary coil part and the secondary coil 44 as 50 may be occasioned by variance of capacity or inductance or both, of the antenna, ground, or of a tube or other element of a radio frequency circuit or of the detective circuit, such adjustment of the rotor coil 17 is attained similarly as set forth more fully hereinabove, with disturbance, of the hub 19 and with certainty and nicety of the desired adjustment.

It will be observed that the coil or coils 44 when secured in position are mounted to locate the axis of the same at an angle to the axis of rotative setting of the rotary coil 17, and accordingly at a given position of its 60 range of setting the rotor coil 17 has its axis

substantially parallel to, or may be located to be substantially in coincidence with, the axis of the coil or coils 44.

In a similar manner, the rotor coil may be mounted for rotary setting by means of a 70 shaft or the like unassociated with any condenser, which such shaft serves as the axis of rotatable setting in lieu of the shaft 11 of the condenser 10.

If desired, the rotational setting of the rotor coil 17 may be effected by suitable gearing connected to the condenser shaft 11 or other shaft in simultaneous and corresponding arcuate variation of setting.

Whereas, I have described my invention 80 by reference to specific forms thereof, it will be understood that many changes and modifications may be made without departing from the spirit of the invention.

I claim.

1. In a multi-stage transformer coupled, radio frequency system, a variable condenser for varying the capacity of the reactance in each transformer secondary circuit, means for varying the self-inductance of each primary and the mutual inductance of each transformer, said self-inductance varying means comprising a relatively fixed primary coil, a relatively fixed secondary coil and a relatively movable primary coil and means for mounting said relatively movable primary coil in relative movable relation to said relatively fixed primary coil and said relatively fixed secondary coil, said mounting means comprising a relatively fixed 90 bracket and an element supported by said bracket in movable relation to said bracket and supporting said relatively movable primary coil.

2. In a multi-stage transformer coupled, 105 radio frequency system, a variable condenser for varying the capacity of the reactance in each transformer secondary circuit, means for varying the self-inductance of each primary and the mutual inductance of each transformer, said self-inductance varying means comprising a relatively fixed primary coil, a relatively fixed secondary coil and a relatively movable primary coil and means for mounting said relatively movable primary coil in relative movable relation to said relatively fixed primary coil and said relatively fixed secondary coil, said mounting means comprising a bracket supported by the shaft of said variable condenser and further comprising an element movably supported by said bracket and supporting said relatively movable primary coil.

3. In a multi-stage transformer coupled, 125 radio frequency system, a variable condenser for varying the capacity of the reactance in each transformer secondary circuit, means for varying the self-inductance of each primary and the mutual inductance of each transformer, said self-inductance varying 130

- means comprising a relatively fixed primary coil, a relatively fixed secondary coil and a relatively movable primary coil and means for mounting said relatively movable primary coil in relative movable relation to said relatively fixed primary coil and said relatively fixed secondary coil, said mounting means comprising a bracket, means for adjustably supporting said bracket relative to the shaft of said variable condenser, said mounting means further comprising an element movably supported by said bracket and supporting said relatively movable primary coil.
- 15 4. A bracket for adjustably setting a movable inductance coil of a radio system, comprising a body portion having an opening for receiving the shaft of a variable condenser, said body portion further having a slot, a movable element disposed in said slot for adjusting the position of said bracket relative to said condenser shaft and means for clamping said movable element in any adjusted position.
- 20 5. A bracket for adjustably setting a movable inductance coil of a radio system, comprising a body portion having an opening for receiving the shaft of a variable condenser, said body portion further having a slot, a worm having an exteriorly disposed manipulating portion, said worm being disposed in said slot for adjusting the position
- 25 of said bracket relative to said condenser shaft and means for clamping said setting worm in any adjusted position.
- 30 6. A bracket for adjustably setting a movable inductance coil of a radio system, comprising a body portion having an opening for receiving the shaft of a variable condenser, said body portion further having a slot, a movable element disposed in said slot for adjusting the position of said bracket relative to said condenser shaft, means for clamping said movable element in any adjusted position and means for mounting said movable inductance coil at an angle to the direction of length of said condenser shaft.
- 35 7. A bracket for adjustably setting a movable inductance coil of a radio system, comprising a body portion having an opening for receiving the shaft of a variable condenser, said body portion further having a slot, a worm having an exteriorly disposed manipulating portion, said worm being disposed in said slot for adjusting the position of said bracket relative to said condenser shaft, means for clamping said setting worm in any adjusted position and means for mounting said movable inductance coil at an angle to the direction of length of said condenser shaft.

In testimony whereof I have signed this specification this 19th day of August, 1925.

FRANCIS L. LORD.
